United States Patent Office

Des. 181,124

Patented Oct. 8, 1957

181,124

BUILDING

Louis J. Catania, West Yarmouth, Mass.

Application July 24, 1956, Serial No. 42,365

Term of patent 14 years

(Cl. D13—1)

Fig. 1

Fig. 2

Figure 1 is a perspective view of a building showing my design; and

Figure 2 is a side elevational view of the same.

The dominant features of my design reside in the portions shown in full lines.

I claim:

The ornamental design for a building, as shown and described,
